SUPPORT ARM FOR INDICATOR GAUGE

Howard L. Hall, 1608 Evans Ave.,
Valparaiso, Ind. 46383

Filed Nov. 20, 1972, Ser. No. 308,019

Term of patent 14 years

Int. Cl. D10—07

U.S. Cl. D10—74

FIG. 1 is a perspective view of the support arm of my design showing the front and right side thereof;

FIG. 2 is another perspective view of the support arm of my design showing the back and left side thereof;

FIG. 3 is a top view; and

FIG. 4 is a bottom view thereof.

I claim:

The ornamental design for a support arm for indicator gauge, substantially as shown.
